Inventor,
John W. Neal.
by Attorney. # UNITED STATES PATENT OFFICE.

JOHN W. NEAL, OF XENIA, KANSAS.

CHURN.

SPECIFICATION forming part of Letters Patent No. 239,825, dated April 5, 1881.

Application filed September 3, 1880. (No model.)

To all whom it may concern:

Be it known that I, JOHN W. NEAL, a citizen of the United States, residing at Xenia, in the county of Bourbon and State of Kansas, have invented certain new and useful Improvements in Churns; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain improvements in that class of rotary churning which are mounted upon a frame and operated by gearing, as seen in the patent of Wm. Robinson, No. 50,631, dated October 24, 1865, as will be hereinafter more fully pointed out in the claim.

The main objects of my improvements are to construct and arrange the parts acting upon the cream so that they shall be within the churn-box, and protect the cream from the deposits of the frictional bearing-surfaces.

Figure 1 of the drawings represents a vertical sectional view of my improved churn. Fig. 2 is a perspective view of the churn-box partially broken away to show the tube extending from the bottom of the box. Fig. 3 is a perspective view of the dasher with the center tube or cap partially broken away to show more fully the socket to receive the upper end of the shaft, and Fig. 4 is a perspective view of the strainer.

In the annexed drawings, forming a part of this specification, the letter A represents the frame having a platform, B, upon which is mounted the churn-box C. To the under side of the platform B are arranged two or more brackets or journal-bearings, to support the operating-gearing. In the bracket or journal-bearing D, which is arranged in the center of the platform, is stepped the vertical shaft E, having near its lower end pinion b, meshing with pinion d, arranged at right angles thereto, substantially as shown in Fig. 1 of the drawings.

The churn-box C is provided with a central tube, F, extending from the bottom of the box to about two-thirds or three-fourths the height

of the box, as seen in Fig. 2. This tube is rigidly attached to the under side of the bottom of the churn-box and passed through an opening in the bottom of the box, thereby supporting it in a vertical position.

The vertical shaft E passes through the platform B and the tube F of the churn-box, so that its upper end, which is square or angular, shall project above the upper surface of the tube to receive a dasher, about to be described.

The letter H represents the churn-dasher, composed of the cross-bars C C, mortised and tenoned together, and their outer ends provided with the downwardly-projecting dasher-arms e. The central portions of the cross-bars are formed with a socket and provided with a tube or sleeve, K, as shown fully in Fig. 3. This sleeve or tube K is designed to fit over tube F so as to make a close joint and prevent the escape of the cream when it is being agitated. This tube also serves to prevent the dasher and central shaft from wabbling during the operation. This dasher is adjusted onto the shaft by fitting the socket i over the upper end of the shaft E, and the tube K passing over the tube F of the churn-box so as to make a close joint.

Within the churn-box is arranged the strainer M, with the ends turned up, constituting a surrounding flange, l, and corresponding in dimensions with the area of the inside dimension of the churn-box. This strainer has a perforated bottom, and is provided at diagonal corners with handles N, to lift it out of the churn. It also has in the center the hole Q, corresponding in size to the tube F, in order that it may be let down into place over the said tube.

Operation: The cover or lid k of the box is removed, and the cream poured into the churn-box until it reaches, or nearly so, the top of the tube F, so that the churn-box shall be two-thirds, or nearly so, full. The dasher, if not already in place, is adjusted in position so the arms e shall extend downwardly. The cover is now replaced to close the churn-box.

It will be seen, by reference to Fig. 1 of the drawings, that the cap of the dasher fits over the tube F, which extends upwardly the dis-

tance of about three-fourths (2) the height of the churn-box, and is within, completely, the box, so that the closed cover *k* can rest upon the top of the box and exclude all dust and foreign matter from dropping in the cream; also, the shaft, having its frictional bearing in the center of the cap, permits all deposits from the bearing to pass down and within the tube *F*, thus enabling me to exclude all foreign matter from the cream during the process of churning.

Motion is imparted to the operating parts through the medium of the gearing, deriving its power from hands or belts.

15 After the churning process the lid is removed and the strainer lifted by means of the handles, which collects the butter as it is drawn out of the churn and permits the escape of the

milk from the same through the perforations in the bottom.

What I claim, and desire to secure by Letters Patent, is—

In a churn, the combination of the churn-box *C*, the cover *k*, and the tube *F* for the passage of the operating-shaft with the churn-dasher *H*, provided with an overfitting cap or sleeve, *K*, said tube *F* and dasher being completely located within the churn-box, as set forth.

In testimony whereof I affix my signature in presence of two witnesses.

JOHN W. NEAL.
